(57) **CLAIM**

The ornamental design for a portion of a game cabinet, as shown and described.

DESCRIPTION

FIG. 1 is a front isometric view of one embodiment of a portion of a game cabinet showing my new design;

FIG. 2 is a front elevational view thereof;

FIG. 3 is a right side elevation thereof;

FIG. 4 is a left side elevation thereof;

FIG. 5 is a front isometric view of an alternate embodiment of a portion of a game cabinet showing my new design;

FIG. 6 is a front elevational view thereof;

FIG. 7 is a right side elevation thereof; and,

FIG. 8 is a left side elevation thereof.

The broken lines are for illustrative purposes only and form no part of the claimed design.
